CLAIM

The ornamental design for a bottle, as shown and described.

DESCRIPTION

FIG. 1 is a perspective view of the bottle showing our new design;

FIG. 2 is a front elevation view thereof;

FIG. 3 is a side elevation view thereof; and,

FIG. 4 is a top plan view thereof.

The broken lines in the drawings illustrate the portions of the bottle that form no part of the claim.

1 Claim, 3 Drawing Sheets
